UNITED STATES PATENT OFFICE.

EDWARD D. MATTISON, OF CHICAGO, ILLINOIS, ASSIGNOR, BY DIRECT AND MESNE ASSIGNMENTS, TO M. & L. NOVELTY COMPANY, A CORPORATION OF ILLINOIS.

FOLDING STAND OR BOOKCASE.

No. 915,618.

Specification of Letters Patent. Patented March 16, 1909.

Application filed June 22, 1908. Serial No. 439,821.

To all whom it may concern:

Be it known that I, EDWARD D. MATTISON, a citizen of the United States, residing at Chicago, in the county of Cook and State 5 of Illinois, have invented certain new and useful Improvements in Folding Stands or Bookcases; and I do declare the following to be a full, clear, and exact description of the invention, such as will enable others skilled 10 in the art to which it appertains to make and use the same.

This invention relates to a device which may be used as a folding stand or book case and has for its object to provide a simple 15 device of this kind which may be arranged as a stand for venders of newspapers, magazines, or other periodicals, or which may be used as a book case.

While the invention is especially designed 20 as a stand for street venders of newspapers, magazines, or other periodicals it is evident that it may be employed in any other connection where it would be adapted.

With these and other objects in view, the 25 invention consists of certain novel features of construction, combination and arrangement of parts, as will be more fully described and particularly pointed out in the appended claim.

30 In the accompanying drawings, Figure 1 is a front elevation of the device arranged as a stand or book case; Fig. 2 is a side elevation thereof; and Fig. 3 is a view similar to Fig. 1 with the shelves folded inwardly 35 and one side folded inwardly against the shelves.

In the embodiment illustrated the stand comprises a flat metallic back piece 1, the upper end of which is of preferably curved 40 form as indicated, and 2 and 3 indicate the side pieces and supporting shelves respectively, the former of which are adapted to fold inwardly against the ends of the supporting shelves when the latter are in horizontal 45 position, the supporting shelves being adapted to fold inwardly against the face of the back piece when the stand is collapsed. The supporting shelves are hinged to the face of the back piece by hinges 4 of any 50 suitable structure while the side pieces are hingedly connected to opposite side edges of

the back piece by upright rods 5, which extend through corresponding eyes produced by bending portions, as 6, of the side edges of the back piece and the inner side edges of the 55 side pieces.

Catches 7, are connected to the outer side edges of the side pieces and are adapted to extend through corresponding apertures 8, produced near the outer corners of the supporting shelves when the latter are in horizontal or supporting position. These catches, as is evident, serve the two-fold purpose of supporting means for the supporting shelves and connecting means for holding 60 the side pieces in connected relation with the supporting shelves when the device is arranged as a stand or book case.

It is to be noted that the upper ends of the side pieces extend above the upper supporting shelf, when the latter is in horizontal or supporting position and constitute end guards for the newspapers or the like, which may be arranged upon the upper supporting shelf in position.

75 A clamp 9, of spring wire and of approximately U-shaped form is attached to the inner face of the back piece and provides a means for holding papers or the like in position while a second corresponding clamp 10, 80 of greater size is attached to the back piece with its arms extending at right angles thereto and provides a means for holding the papers upon the upper supporting shelf.

85 From the foregoing description, taken in connection with the accompanying drawings, the construction and operation of the invention will be readily understood without requiring a more extended explanation.

Having thus described my invention, what 90 I claim as new is:—

A folding stand or book case comprising a back piece, a series of supporting shelves, provided, each, near its outer corners with vertical apertures, hinged to the face of the 95 back piece and adapted to fold inwardly against the same, side pieces hinged to opposite side edges of the back piece and adapted to fold inwardly against the ends of the shelves, and catches horizontally pivoted to 100 the outer edges of the side pieces and having up-turned hook portions to enter the aper-

tures of the supporting shelves, said catches serving the double purpose of supporting means for the shelves and as means for connecting the side pieces therewith, the catches being adapted to fold inwardly against the supporting shelves when the stand or book case is collapsed.

In testimony whereof I have hereunto set my hand in presence of two subscribing witnesses.

EDWARD D. MATTISON.

Witnesses:

JULES LANGTH,
OTTO MOELLER.
